UNITED STATES PATENT OFFICE.

ANDREW P. TUCKER, OF CINCINNATI, OHIO, ASSIGNOR OF ONE-HALF TO MAXMILLIAN ZIMMERMAN, OF CINCINNATI, OHIO.

MACHINE FOR MAKING PAPER FORMS.

1,297,971.

Specification of Letters Patent. Patented Mar. 18, 1919.

Application filed June 2, 1916. Serial No. 101,327.

To all whom it may concern:

Be it known that I, ANDREW P. TUCKER, a citizen of the United States, residing at the city of Cincinnati, in the county of Hamilton and State of Ohio, have invented certain new and useful Improvements in Machines for Making Paper Forms.

The object of my invention is to produce paper forms of a continuous formed sheet which may be cut into lengths.

The paper form or continuous sheet to be substantial and permanent must be hard and stiff and ironed and calendered, so that the form will hold its contour and shape and become capable of resisting outside strains and pressure and not yield readily to jars and sudden impact; retaining at all times a degree of rigidity requisite for the use it is intended to fulfil.

In order to produce such a form I use a large heated female forming roll with its entire periphery formed of depressions for receiving the form and a multiplicity of small heated male forming rolls disposed around the female forming roll each having a continuous formation of male formers which fit the female roll depressions, in this way a continuous pressing, embossing, ironing and calendering is provided and when the form passes through these rolls it is of the required degree of rigidity and firmness and has an ideal body.

In the drawings:

Figure 1, is a side elevation of the machine, showing the driving mechanism.

Fig. 2, is a front elevation of the back end of the machine.

Fig. 3, is a section of the machine, partly in elevation, it being taken at the opposite side of the view shown in Fig. 1,

Fig. 4, is a section on line 4—4 of Fig. 1, and

Fig. 5, is a side view of the machine which forms a continuous sheet which is operated upon after it passes through the forming rolls and produces a form varying somewhat in contour, and being known as corrugated paper.

This invention relates particularly to the feeding, ironing, calendering and embossing rolls of the machine. The strip of material which is to be acted upon by the present invention may be prepared by any suitable mechanism which will bring it into a condi-

tion ready to be acted upon by the forming rolls.

The frame or base of the machine is marked 1 and is of any preferred form. In order to carry out my construction, I provide housings 2 in which I journal two feed rollers 3 and 4, carrying at one side the gears 5 and 6. I also provide a large housing 7 in which I journal the large female forming roll 8, provided with continuous peripheral depressions or female dies 9; this roll 8 is hollow to enable it to be heated, and on a hub 10 of roll 8, I fasten a gear 12.

I surround this large roll 8 with a multiplicity of smaller male rolls 13, all of the same formation, each carrying the male formers or dies 14, each, in the present instance, having eight of such formers, in Figs. 1, 2, 3 and 4, but in Fig. 5 carrying a greater number thereof.

Each of these male forming rolls 13 is journaled in the housing 7 and at one side each carries a hub 15, on which is placed a gear 16. These small or male rolls 13 are each hollow in order that they may be heated. I show one form of heating means, 80 which I attach to the machine in any desired manner, and shown in Fig. 4 particularly. To provide these heating means, I provide a main gas intake pipe 17, provided with short pipes and valves 18, which carry the gas to the burners 19 which extend with all the rolls, and when lighted heat all said rolls to the required intensity.

On the inside of the machine and extending arms of the same, is an apron 20 supported on pins or the like 21. I do not need this construction, however, in Fig. 5.

I further provide a housing 22, on which I support or journal a roller 23 and a female roller 24, having the depressions 25 into which the finished form fits. On this roller 24, at two of its edges where two of the depressions meet, I place knives 26. These knives extend somewhat above the edges of the female roller 24. On the shaft 27 of roller 24, I place a gear 28 and on the shaft 29 of roller 23, I place the gear 30. When I use machine shown in Fig. 5, I do not need this cutting or severing mechanism.

On the hub 15 of large roll 8, I place a sprocket 31 and on the roll 24, I place a sprocket 32, the sprocket chain 33 passing over and engaging said sprockets.

In order to thread the machine, I provide, on one of the rolls 13, a stud shaft 34 carrying an eccentric bush 35 which carries an extending arm 36, on which arm is a bar 37, 5 said bar extending across the machine. The strip of material is marked 38 and is fed into the rolls of the machine through rollers 3 and 4, making a loop 39, which loop always provides the required amount of material for the forming rolls, so that it will 10 not come from the feeding rolls; when the strip of material reaches the first male roll 13, said roll is lifted through the agency of the eccentric bush 35 and its connection being lifted, raising the roll 13 and when thus 15 lifted or elevated the material 38 is slipped into position between said first roller 13 and the large roll 8; the eccentric bush and connections then are brought into normal position, thus lowering the roll 13, the strip of 20 material 38 is gripped and passes onward between the forming rolls. The strip 38 is fed and feeds itself around through and between the small forming rolls 13, and the 25 large forming roll 8 and when it leaves them passes onto the supporting apron 20, then passes up through rollers 23 and 24 and when one of the knives 26 meet the formed strip 38 between the roller 23 and the roller 30 24 it cuts off a finished form of any length.

In operation, power is applied in any desirable manner to large former roll 8 to revolve or rotate the said roll; this rotation revolves the gear 12 on said roll, which gear 35 meshes with each of the gears 16 on the male forming rolls 13 and thus all said rolls 13 are forced to revolve or rotate, the formers 14 on said rolls fitting into the depressions 9 in roll 8 and thus the form is shaped between said rolls. The revolution of the 40 large forming roll 8 also revolves the sprocket wheel 31 over which the sprocket chain or belt 33 operates, and said belt also passing over and engaging the sprocket 45 wheel 32 on roll 24 revolves said roll 24 and forces the gear 28 to mesh with the gear 30 on roller 23, and thus motion is imparted to said rollers 23 and 24, forcing them to revolve. The feed rolls 3 and 4 carrying the 50 gears 5 and 6 may be operated in any desired manner, but are generally operated by the mechanism which operated the complete machine, no mechanism being shown in the drawing for operating them, as it is not 55 essential to the disclosure of my invention.

In Fig. 5 I show the rolls forming the sheet into a somewhat different contour, and do not show any mechanism for severing the sheet but illustrate a pasting apparatus 60 for facing the finished strip or sheet when it comes from the forming roll. I will describe this particular device in detail.

On base 1, in Fig. 5, I provide a housing 40 in which I journal the two sets of paste 65 rollers 41 and 42, revolving as shown by

arrows. These sets of paste rollers receive the paste from the paste troughs 43 and 44, through the agency of paste rollers 45 and 46.

At front of machine I provide a roll of 70 paper 47 which is to be corrugated, supported in a frame 48 upon which it revolves. In brackets 49 I revolvably support paper rolls 50 and 51.

The paper to be corrugated passes through 75 the forming rolls 8 and 13, and is marked 38, when it has passed through said rolls, it is corrugated in contour and the product here is marked 52. The paper 53 and 54 off of the rolls 50 and 51 passes over the 80 rolls 55 and 56, and as it thus passes over said rolls comes in contact with the paste rolls 41 and 42, they receiving the paste, the rolls 55 and 56 pressing it onto said corrugated paper sheet 52; the finished product 85 being marked 57.

The rolls 8 and 13 for making the formation, as shown in Fig. 5, have the formers and depressions on their face or periphery of a different contour than those shown in 90 the other figures.

The large female forming roll operates in one direction and the small male forming rolls operate in an opposite direction.

Paper can be formed up under these heat- 95 ed forming rolls very rapidly and at the same time the product is of a high class as it is perfectly formed and has a solid and smooth surface and has a texture highly efficient for use in forming articles for which 100 the same is intended in a commercial way.

It will be understood that I can make the formers and depressions of the various rolls of any desired configuration, so that paper forms other than the ones specifically herein 105 referred to, may be produced by my invention.

From the above description it will be seen that the improved machine for making paper forms constructed according to my in- 110 vention is of an inexpensive and extremely simple nature and is especially well adapted for the purpose for which it is designed, and it will also be obvious from the above description that the machine is capable of 115 considerable modification without material departure from the principle and spirit of the invention, and for this reason I do not wish to be understood as limiting myself to the precise form and arrangement of the 120 several parts of the machine as herein set forth in carrying out my invention in practice.

What I claim as new and my invention and desire to secure by Letters Patent is: 125

1. In a machine for making paper forms, a rotary forming roll, provided with continuous depressions, a series of forming rolls each provided with a continuous set of formers on their periphery, the formers on the 130

latter rolls fitting into the depressions of the forming roll, and of said series of forming rolls provided with means for raising and lowering the same in order to thread 5 said rolls with the material, and means for revolving all said rolls.

2. In a machine for making paper forms, a large, single, heated female forming roll and a series of male heated forming rolls 10 surrounding said female forming roll at its

periphery and disposed around the upper half of said forming roll, all coacting together to press a paper form between them, and means for rotating all said rolls.

Witness my hand at Cincinnati, Ohio, 15 May 23, 1916.

ANDREW P. TUCKER.
